DESIGN FOR A DISPLAY FIGURE

William L. Stensgaard, Chicago, Ill., assignor to
The Diamond Match Company, a corporation of Delaware

Application April 13, 1945, Serial No. 118,979

Term of patent 14 years

(Cl. D80—8)

To all whom it may concern:

Be it known that I, William L. Stensgaard, a citizen of the United States, residing at Chicago, in the county of Cook and State of Illinois, have invented a new, original, and ornamental Design for a Display Figure, of which the following is a specification, reference being had to the accompanying drawing, forming part thereof.

I claim:

The ornamental design for a display figure, as shown.

WILLIAM L. STENSGAARD.
